UNITED STATES PATENT OFFICE.

WILLIAM SEVERNS, OF CHICAGO, ILLINOIS.

YARN-WINDING MACHINE.

Application filed August 17, 1921. Serial No. 493,014.

To all whom it may concern:

Be it known that I, WILLIAM SEVERNS, a citizen of the United States, and a resident of the city of Chicago, in the county 5 of Cook and State of Illinois, have invented a certain new and useful Improvements in a Yarn-Winding Machine; and I do hereby declare that the following is a full, clear, and exact description of the same, reference 10 being had to the accompanying drawings, and to the numerals of reference marked thereon, which form a part of this specification.

This invention relates to improvements in 15 a machine for winding yarn and is especially adapted for use with those yarn winding machines adapted for the production of mops or the like.

One of the objects of this invention is the 20 provision of a machine for winding yarn which is so constructed that it will be automatically stopped whenever a string of the yarn which is being wound by the machine breaks.

25 Another important object of this machine is the provision of means whereby yarn is wound in an even regular manner upon a frame provided therefor, which frame is removable from the machine and which yarn is wound upon said frame in a plurality of 30 layers and with a plurality of strings of yarn being fed to the frame at the same time.

Another important object of this invention 35 is the provision of a machine for winding yarn having mechanisms adapted to automatically stop the same when a sufficient desired quantity of yarn is wound upon the frame in the machine, which quantity can be predetermined.

Still another important object of this machine is the provision of means whereby the yarn which is wound on a frame in the machine is placed thereon in such position 45 and in such regular order that it is adapted to be immediately stitched together and then cut into strands ready to be formed into a mop.

Other and further important objects of 50 the invention will be apparent from the disclosures in the accompanying drawings and following specification.

The invention (in a preferred form) is illustrated in the drawings and hereinafter more fully described.

55

On the drawings:

Figure 1 is a side elevation of the assembled machine.

Figure 2 is a front view of the same.

Figure 3 is a top plan view.

60

Figure 4 is a diagrammatic view of the electrical circuits.

Figure 5 is a section taken on the line 5—5 of Figure 1.

Figure 6 is a section taken on the line 65 6—6 of Figure 2.

Figure 7 is a sectional view taken on the line 7—7 of Figure 2.

Figure 8 is a section taken on the line 8—8 of Figure 1 looking in the direction 70 indicated by the arrows.

Figure 9 is a section on the line 9—9 of Figure 1 looking in the direction indicated.

Figure 10 is a section on the line 10—10 75 of Figure 7.

Figure 11 is a detail view showing the construction of the automatic stop mechanism.

As shown on the drawings:

The reference numeral 15 indicates the 80 base of the machine consisting of a rectangular frame with supports at each corner thereof. Mounted above the frame and at a distance slightly behind the same is a support 16 preferably in the form of a bracket extending from a wall or the like upon which is mounted a collapsible wheel or reel 18 adapted to support a skein of yarn 20. This reel 18 is revolvably mounted by means 85 of an axle 22 removably placed in bearings 24 in the bracket 16. Any desired number of reels may be used. Adapted to guide and support the strings of yarn 20 as they are unwound from the reels 18 is a plurality 90 of uprights 26 made of wood or metal set into the base of the frame 15, and attached to the end of each upright is a flexible wire 28 having a loop at the end thereof through which a string of yarn is adapted to be 95 passed.

Movably mounted at the top of the frame 15 is an arm 54 supporting a bracket 30 having thereon loops 32 for the reception of the 100

strands of yarn after they pass through the loops on the ends of the uprights 26-28. This arm is also provided with upwardly extending plates 34 (Figure 7) adapted to support transversely extending rods 36 and 38. The lower rod 38 has pivoted thereon a plurality of rocker members 40 each consisting of a pivoted arm having at its end a loop or port 42 through which the yarn 20 passes as shown in Figures 7 and 10 and at the other end of the arm 40 is attached a counterweight 44. These rocker arms 40 are slidably fixed in position upon the shaft 38 by having mounted upon the shaft lugs or the like 46 which are held in position by set screws 48 in order to maintain the rockers 40 in any desired spaced position. As shown in the figures, three of these rockers 40 are mounted on the arm 38 but it will be obvious that any number of them may be employed as desired.

A contact point 50 is provided on each rocker arm 40 for coaction with a corresponding point on the rod 36 when the rocker arm 40 has been thrown up into the position shown in the dotted lines in Figure 7 by reason of the action of the counterweight 44 on account of the release of the arm by the breakage of the string of yarn 20. An additional loop 52 is provided at the lower end of the bracket 30 to additionally guide the string 20. The bracket 30 and the plate 34 are all fixed by means of screws 53 to the slideable rod 54 which extends longitudinally across the top of the machine and the rod 36 is insulated from the remaining parts of the bracket by means of insulating washers 55 as shown. The supporting rod or arm 54 is adapted to be reciprocated across the top of the machine by means of a heart-shaped cam 56 cooperating with a projection or roller 58 mounted in the rod as best shown in Figures 2 and 3, and the rod itself is slidably mounted in suitable bearings 57 on the frame 15 as shown. The cam 56 is eccentrically mounted on a vertical driving shaft 60, this shaft in turn being revolved by means of a gear 61 coacting with a worm wheel 63 on a horizontal shaft 62 (Figure 5), which shaft 62 is in turn driven by a similar gear 65 thereon (Figure 2) which coacts with a worm 64 on the main driving shaft 66 (Figure 3), which is driven by a pulley or the like 67 having fixed thereon a clutch member 68, the operation of the clutch being controlled by a lever 69 (Figure 2). This lever 69 is normally held in retracted release position by means of a spring 70, but it has fixed thereon a hook attachment 71 coacting with a similar hook on the end of a soft iron rod 72 pivoted at 73 to a bracket on the frame 15 of the machine and having its other end spring-held in downward position by means of a spring 74. Mounted

immediately above the spring-held end of the rod 72 are a pair of electro-magnets 75 which cooperate with the rod 72 to draw the same into an upward clutch releasing position whenever a circuit is closed through them.

The end of the driving rod 66 terminates in a form of lathe arrangement and is mounted in a bearing 76. Mounted in a similar aligned bearing 77 at the other side of the machine is a rotatable spring-pressed cooperating member 78 having a handle or wheel 79 by which it may be manipulated. This lathe arrangement is adapted to rotate a frame 80 rectangular in form, and upon which is wound the three strands of the yarn 20 delivered from the reels 18. The construction and arrangement of this frame 80 is more fully described in my co-pending application for "process of making mops," Serial No. 493,012 filed Aug. 17, 1912.

Mounted on the rearwardly extending end of the shaft 62 is a beveled gear 82 adapted to cooperate with a similar beveled gear 83 mounted on the bottom of the vertically extending screw-threaded shaft 84 as best shown in Figures 1 and 11. An upwardly extending rod 85 is mounted parallel to the screw-threaded shaft 84 and slidably positioned upon said rod is a block of insulating material 86 held in position thereon by means of a set screw 87 as best shown in Figure 9. A metal member 88 is fixed to the insulating block 86. Adapted to cooperate with this contact member 88 is a corresponding contact member 89 mounted upon a movable block 90 slidably mounted on the rod 85 and provided with a half round screw-threaded section 91 as best shown in Figure 8. This half round screw-threaded section 91 is internally threaded and is adapted to cooperate with threads on the rod 84. A handle 92 is pivoted at 93 on the block 90 and is held in outward position by means of a coiled spring 94 for the purpose of maintaining the screw-threads in the half-round block 91 in contact with their corresponding threads on the shaft 84. A wire 95 leads from the insulated rod 36 to the magnet 75 and from thence to a battery 96 which has its other terminal grounded to the machine at any convenient point. The contact points 50 on the rockers 40 are not insulated from the frame. Another wire 97 also leading to the magnet 75 and the battery 96 is connected to the insulated contact member 88 which cooperates with the contact member 89 grounded to the frame of the machine.

The operation is as follows:

A collapsible reel 18 is first inserted into a skein of yarn 20 and then threaded through the loop in the support 26, 28 as shown in Figure 1 whereby the yarn 20 is held in position ready to be reeled off to the frame

80. Three of these reels 18 are provided in the preferred machine, each having a thread 20 leading therefrom. Each of these threads 20 passes through a loop in the end 5 of an upright member 26, 28 as shown in Figure 1 and thence to a loop 32 in the bracket 30, as shown in Figures 1 to 7. The yarn is then led over the rod 36 and passed through the guide members 42 on the end 10 of a rocker 40, after which it is led through a loop 52 as shown in Figure 7, to properly guide it onto the reel 80. The reel 80 is rotated by means of its connection with the main driving shaft 62, the speed and timing 15 being properly adjusted, and at the same time the supporting arm 54 holding the brackets 30 and 34 with their connected members in position is reciprocated back and forth across the machine to a predetermined degree, (in this case 5 inches) by 20 means of the action of the groove in the heart-shaped cam 56 cooperating with the projection 58 upon the arm 54. This results in the forming of a plurality of evenly 25 placed layers of the yarn 20 on the reel 80. The rotation of the shaft 62 also causes a rotation of the threaded rod 84 by means of the beveled gears 82 and 83 and this results in an upward movement of the member 90 30 on the threaded rod 84. The contact member 88 on the block 86 is so positioned that when a predetermined amount of yarn has been wound on the reel 80 the member 89 will contact with the point 88 causing a 35 making of the circuit in the wire 97 which actuates the magnet 75 which thereupon acts to draw up the free end of the arm 72 against the tension of the spring 74 disengaging the hook 71 and allowing the spring 70 to retract the arm 69 thereby releasing the clutch 40. In this manner the operation of the machine is automatically stopped and the amount of yarn delivered to the reel or frame 80 is controlled. 45
- In case one of the threads 20 breaks the rocker 40 will be immediately released and its counterweight 44 will throw it upwardly into the position shown in the dotted lines in Figure 7 and the contact point 50 will 50 come into cooperation with its correspond-
- ing contact point on the insulated rod 36 thereby making a connection through the wire 95 to the battery 96 and through the magnet 75 which will operate to release the clutch 68 in the same manner as has heretofore been described. 55
- It will be seen that the operation of this machine is entirely automatic, the same being controlled both as to the amount of yarn fed onto the reel or frame 80 and also automatically stopped upon the breakage of any of the strings 20 by means of the electrically arranged mechanism and contact members and that waste of time and consequent loss of material due to breakage of the yarn 20 60 is entirely eliminated, and further an automatic regulation of the amount of yarn to be fed to the frame 80 will be readily accomplished. Suitable switches may be provided for controlling the current, and the member 90 may be readily reset by gripping the handle 92. 65
- I am aware that many details of construction may be varied through a wide range without departing from the principles of 70 this invention, and I therefore do not purpose limiting the patent granted hereon, otherwise than necessitated by the prior art. 75
- I claim as my invention:
- In a yarn winding machine, a winding 80 reel, a driving shaft therefor, a rotatable member operatively connected to said shaft, a clutch for controlling said shaft, solenoid operated means for releasing said clutch upon the breaking of a yarn, and a contact 85 element adjustably mounted upon said rotatable member and movable relative thereto during the rotation thereof for effecting an electrical connection for energizing said solenoid for releasing said clutch after a 90 predetermined amount of yarn has been wound. 95

In testimony whereof I have hereunto subscribed my name in the presence of two subscribing witnesses.

WILLIAM SEVERN.
